UNITED STATES PATENT OFFICE.

HENRY C. MOORE, OF TAMA CITY, IOWA.

ROAD-SCRAPER.

SPECIFICATION forming part of Letters Patent No. 250,945, dated December 18, 1881.

Application filed August 10, 1880. (Model.)

To all whom it may concern:

Be it known that I, HENRY C. MOORE, of Tama City, in the county of Tama, and in the State of Iowa, have invented certain new and useful Improvements in Road-Scrapers; and I do hereby declare that the following is a full, clear, and exact description thereof, reference being had to the accompanying drawings, making a part of this specification, in which—

10 Figure 1 is a perspective view of my improved scraper as arranged for use. Fig. 2 is a plan view of the upper side of the same. Fig. 3 is a side elevation of said device, and Fig. 4 is an enlarged perspective view of one of the swiveled clamps used for connecting the scraper to the draft-beam.

Letters of like name and kind refer to like parts in each of the figures.

The design of my machine is to enable roads 20 to be easily constructed and kept in proper shape; and to this end it consists, principally, in the means employed for connecting the scraper to or with the draft-beams and for varying the cutting-angle of said scraper, substantially as and for the purpose hereinafter specified.

It consists, further, in the means employed 25 for connecting the scraper to or with the frame of the machine, and varying its angle with relation to the line of draft, substantially as and for the purpose hereinafter shown.

It consists, further, in the combination of the 30 scraper, connecting mechanism, and elevating devices with the frame of the machine, substantially as and for the purpose hereinafter set forth.

It consists, finally, in the means employed 35 for preventing side draft of the scraper, substantially as and for the purpose hereinafter shown and described.

In the annexed drawings, A and A' represent 40 two rails, which are arranged in parallel lines, and are connected together by means of two cross-bars, B and B', that extend between and are secured to the same at points between their 45 longitudinal centers and ends. Each rail A is stiffened vertically by means of a truss, A', which extends between its ends at its upperside, while at their ends said rails rest upon and are secured to bolsters C and C', that are in turn sup- 50 ported by or upon a front and rear axle, D and

E, respectively, that are provided with ground-wheels F, of usual construction, said parts forming the supporting-frame and running-gear of my machine.

Arranged transversely beneath the frame described, between the front and rear wheels, is a scraper, G, which has a length somewhat greater than the track of the machine, and longitudinally a straight face, and transversely has a curved face, its concave side being in front. 55

Upon the rear side, at or near the upper edge, near the ends of the scraper G, is a U-shaped bar, H, which is so secured to the scraper as to allow it a swiveling movement upon said scraper, and at its ends it is threaded and provided 60 with nuts h, and said ends spanned by means of a clamp, h', the arrangement being such as to enable said bar to turn upon the crown of the bend as a bearing, so as to present the opening between its arms at any desired angle 65 oblique to a horizontal plane.

Pivoted upon the king-bolt d is a plate, I, which has two diverging arms, i and i', that have unequal lengths and extend rearward. Within the rear end of each arm i and i' is 70 pivoted one end of a bar, K, which at its opposite rear end, k, has a downward and forward curve, and fits into one of the clamps, H, where it is securely held by screwing up the nuts h, the said curved portion or end k being 75 caused to correspond to and embrace the convex rear side of the scraper G.

The construction of the rear end of the draft-bar K enables the vertical angle of the scraper G to be varied at will, to accomplish which it 80 is only necessary that the clamps H be loosened, and said scraper turned upward or downward upon said bar until in the desired position, after which the tightening of said clamps again secures said scraper in place. The unequal lengths of the arms i and i' enable the scraper G to be set at an oblique angle with relation to the line of draft, while the draft-bars K have equal lengths, while by the employment of bars of different lengths, or by providing one or both of said arms with a series 85 of pivotal springs that have relatively different distances from the king-bolt d, any desired angle may be secured. It will be observed 90 that in changing the angle of said scraper 95 100

the rear ends of said draft-bars swivel within the clamps H and adapt themselves to any change of relative position. The scraper thus attached to the frame of the machine is free at 5 either end to move vertically in order to conform to the undulations of the ground, its connection with said frame being flexible; but in order that such vertical movement may be limited, and that, when desired, said scraper may 10 be raised from contact with the ground, the following described means are employed, viz: Two levers, M and M, having an L shape in side elevation, are pivoted upon the inner faces of the rails A and A in such position that 15 when their long arms are placed vertically and their short arms extend horizontally rearward the ends of said short arms will be in line with the upper edge of the scraper G. Pivoted to and extending between the rear end of the 20 short arm of each lever M and the upper edge of the scraper G is a rod, m, which connects said parts together, and enables the end of said scraper to which said lever is connected to be adjusted vertically with relation to the 25 frame of the machine, to effect which result it is only necessary that the upper arm of said lever should be moved forward or rearward. A suitable stop device being provided for each lever, the latter may be locked in place, so as 30 to hold said scraper at any point between the limits of its motion.

In order that the scraper G may be prevented from dropping below the lower limit of its motion, and at the same time left free to rise and 35 pass over an obstruction, a chain, N, is secured to each of its ends, and extends upward to and is connected with a hook, O, that projects outward from the adjacent rail.

When the machine is used for trimming one 40 side of a road the outer end of the scraper requires to be lower than its inner end, and such adjustment is effected by means of the chains N, which are lengthened or shortened as required. A third chain, P, attached at the rear 45 outer end of the scraper G, and from thence extending to and engaging with a hook, Q, that projects from the rear axle, E, operates to prevent said scraper from being twisted by the greater pressure against its lower edge than 50 against its upper part.

In order that side draft of the scraper may be prevented, a bar, R, is secured at one end upon the frame of the machine, and extends

diagonally outward and forward in front of the rear end of said scraper, an angle-iron, S, being attached to the side rail, A, and extending beneath said bar for its proper support at such point. 55

From the outer end of the bar R a chain, T, extends rearward to and is connected with the upper edge near the rear end of the scraper G, and operates to prevent side movement of the latter and to hold it firmly to its work. After the soil has been worked upon the shoulder of the road the scraper G may be adjusted to a 65 position at or near a right angle with the line of draft, and the central part of said road worked, if desired.

Having thus fully set forth the nature and merits of my invention, what I claim as new 70 is—

1. In combination with the scraper G, having a vertically-convex rear side, and having swiveled therein the clamps H, the draft-bars K, provided with curved rear ends, k, which 75 conform to and embrace the rear side of said scraper, substantially as and for the purpose specified.

2. As a means for connecting the scraper G to or with the frame of the machine, the pivoted 80 plate I, having diverging arms i and i', the draft-bars K k, the lifting-levers M, the connecting-bars m, the chains N, and the hooks 85 O, all combined to operate substantially as and for the purpose shown.

3. In combination with the frame of the machine, the scraper G, the pivoted plate I i i', the draft-bars K k, the lifting-levers M, the connecting-bars m, the chains N, and the hooks 90 O, all combined to operate substantially as and for the purpose set forth.

4. In combination with the scraper G, the bar R, projecting diagonally from the frame of the machine in front of said scraper, and the 95 chain S, extending between the latter and the outer end of said arm, substantially as and for the purpose specified.

In testimony that I claim the foregoing I have hereunto set my hand this 6th day of 100 March, 1880.

HENRY C. MOORE.
